UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

MACHINE FOR MAKING CARD-MATCHES.

1,217,993.

Specification of Letters Patent. Patented Mar. 6, 1917.

Application filed July 13, 1916. Serial No. 109,160.

To all whom it may concern:

Be it known that I, MICHAEL PARIDON, a citizen of the United States, and resident of Barberton, in the county of Summit and State of Ohio, have invented certain new and useful Improvements in Machines for Making Card-Matches, of which the following is a specification.

This invention relates to machines for making card matches composed of a series of matches and a common marginal portion to which the splints are frangibly connected at one end. A machine for this purpose is illustrated in Patent No. 636,170, dated October 31, 1899, by reference to which it will be seen that mechanism is provided whereby stock is drawn from a roll and fed to splint-cutting devices by means of which successive match cards are partially formed, each card having alternate splints "staggered" and cut from the stock, the others being attached at one end to the stock. The marginal part of the card is advanced to and placed in an endless carrier and the series of attached splints are then separated from the stock during the splint-forming operation on a succeeding card portion of the stock, and so on. The carrier, with the match cards thus inserted therein in spaced relation to each other, transports the cards through the match making path, including means for applying composition to the free ends of the splints, and thence to a discharge station where the complete card matches are successively removed from the carrier.

My present invention particularly concerns the match card carrier, and it has for its object to provide a carrier of such character that the flexible marginal portions of the cards can be applied thereto without liability of breaking or buckling the card material and yet the cards shall be firmly and securely held by the carrier and can be readily discharged therefrom without injury to the material.

Another object of my invention is to provide a carrier whereby each match card with its staggered alternate splints shall be held in such position relatively to the carrier that the free ends of the splints will travel in the same horizontal plane across the path of a "dipping" roller and the application of substantially uniform "heads" to the splints thus be insured.

With these objects in view my invention

comprises a match card carrier having pairs of rigid walls and complementary spring clips supported therebetween in spaced relation to each other in such manner that the marginal edge of a match card can be readily inserted between each wall and the proximate yielding limbs of the clips; such a carrier having punch ways adjacent the edges of the limbs of each clip, whereby the ejecting punches may be arranged in pairs so as to act uniformly upon the cards at points adjacent the clamped portions thereof, and such a carrier wherein the inner faces of the rigid walls are sloped or inclined from their inner to their outer edges so as to support the margins of the cards at an angle to the vertical during the horizontal travel of the carrier across the "dipping" roll; all as will be hereinafter described and claimed.

In the drawings—

Figure 1 is a vertical section of a part of a card match machine equipped with a carrier embodying my invention, only so much of the mechanism being shown as is necessary to illustrate the improvement.

Fig. 2 is a perspective view of one of the links of the carrier.

Fig. 3 is a transverse vertical section, through the link, as on the irregular line 3—3 of Fig. 2, showing match cards therein, and a discharging punch about to act upon one of the cards.

Fig. 4 is a bottom view of one of the links, showing the cards therein; an adjoining link being indicated in dotted outline.

Fig. 5 is an edge view of a portion of a link with a card therein, showing the relation of the punches to the clamps.

Fig. 6 is a view of a part of the horizontal run of the carrier with match cards therein, indicating the relation of the ends of the splints to the composition-applying roller.

Referring to the drawings, 10 designates splint-cutting mechanism comprising in the form shown complementary upper and lower die members 11, 12, respectively, between which match-card stock 13 is intermittently advanced from a suitable roll by means of feed-rollers 14.

The die members are of such character that in the descent of the upper member the stock is severed lengthwise in parallel lines throughout its width to produce a row of "splints" having a common marginal portion at the leading end of the stock; the al-

ternate splints of the row being severed from the body of the stock and deflected below the others, or "staggered." The vertically-reciprocative head carrying the upper die member bears a cutter 15 which is so located in relation to the dies as to act upon the stock along the outer edge of the marginal portion of the card as the stock is successively advanced to and beyond the dies by the feed rollers, 10 such cutter thus severing from the body of the stock the ends of the upper series of splints which are attached thereto.

In each feed movement of the stock, and before the action of the dies and the cutter 15 thereon, the marginal portion of the leading card is inserted into an endless carrier 16; whereupon the upper die member descends and the cutter severs the match card transversely from the stock. The carrier is 20 intermittently movable in a path at right angles to that of the stock so as to present appropriately spaced card-receiving portions to the successive cards.

With the exception of the carrier and its 25 adjuncts hereinafter described the parts above referred to are or may be similar in construction and operation to the corresponding parts of the machine set out in Patent No. 636,170 aforesaid.

30 The carrier comprises an endless chain of link members which are supported and guided in any suitable manner throughout the match-making path. Each member is preferably an integral structure comprising 35 two end portions 17 rigidly connected by a pair of spaced parallel jaw bars 18; each end portion being provided with suitable ears 19 whereby adjoining links can be pivotally connected, and also with rack-teeth 40 20 which are adapted to mesh with gear wheels 21 (Fig. 1) whereby the carrier is intermittently driven. The inner or lower edges of the bars 18 are connected at intervals by cross-pieces 22, of which in the present 45 instance three are shown. Rising between the bars from each of these cross-pieces is a post 23, upon which is secured a substantially U-shaped spring 24 the limbs of which straddle the post and bear yieldingly against the inner faces of the respective bars, whereby the margin of a card can 50 be readily inserted edgewise between the springs and the opposing inner wall of a bar. As the springs are well separated—one being 55 at or about the middle of the link and the others at or near the respective ends of the link,—and as the connection or "fulcrum" of each spring is some distance in advance of the point where the edge of the card impinges against the spring, the series of 60 springs readily yield to the pressure of the card thereagainst and thus permit the uniform positioning of the card and its efficient clamping between the springs and the proximate wall of the link bar, without liability 65

of bending or buckling the flexible card material.

The inner walls of the bars are slightly inclined outwardly throughout at least the length of a card, as indicated at 25, that is, the inner walls of each pair of bars parallelly incline throughout the whole or the greater part of their length in order that the margins of the cards shall be maintained slightly out of perpendicular to the body of the link, and thus insure the passage 75 of the free ends of the pendant splints in the same horizontal plane across the path of the usual "dipping" roller 26 which applies the head composition to the matches. 80 Thus substantially uniform "heads" are applied to the splints. (See Fig. 6). This mode of backing or supporting the margins of the cards is important, as owing to the inclination of alternate splints to the surface 85 of their marginal connection, the free ends of such splints would be slightly higher than the others if the margin were supported at a right angle to the horizontal path of the carrier, and in consequence irregular 90 heading of the splints would result, that is to say, the ends of the inclined splints would receive from the dipping roll less composition than the others.

In order to discharge the complete card 95 matches from the carrier when they have been advanced to the discharging station, directly above the splint forming mechanism, I employ a horizontally reciprocating punch head 27 such as is common in wood match 100 machines, and I arrange the punches 28 of this head in pairs which are so spaced in relation to each other and to the clamping springs that each pair of punches in its active stroke impinges centrally against 105 the opposing edge of the margin of the card at points adjacent the respective edges of each clamping spring. The punches do not contact with the springs but act directly on each card at points in proximity 110 to the respective clamps so as to eject the card uniformly and positively from the carrier; the inner side walls of each link being provided with suitably-disposed semi-circular recesses 29 for the passage and guidance 115 of the punch ends.

The card matches as rapidly as they are discharged from the carrier fall upon a suitable take-off conveyer 30. (Fig. 1.)

I claim—

1. The combination with a match card carrier comprising a rigid jaw bar, and a plurality of spring members arranged in spaced relation to each other so as to co-act with the inner face of the bar to clamp an interposed match card at different points, of punch mechanism, including punches arranged in pairs corresponding in number with the said spring members, each pair of punches being movable in paths adjacent to 125 130

and out of contact with the respective edges of a spring member.

5 The combination with a match card carrier comprising rigidly connected parallel clamp bars, and a series of spring members supported in spaced relation to each other between said bars, said members having card-engaging portions which extend adjacent to the inner faces of the respective bars, of punch mechanism, including punches arranged in pairs corresponding in number with the card-engaging portions, each pair of punches being movable in paths embracing a card-engaging portion.

10 3. In a carrier for match cards each composed of a marginal portion and splints whereof alternate splints are deflected from the plane of the marginal portion, a clamp bar having an inclined bearing surface, and 20 springs arranged to clamp the marginal portion of a match card against said surface.

15 4. In a carrier for match cards each com-

posed of a marginal portion and splints whereof alternate splints are deflected from the plane of the marginal portion, rigidly 25 separated parallel jaw bars having inclined inner surfaces, and a series of spring members extending adjacent to the inner surfaces of the respective bars,

5. A match-card carrier embodying hinge- 30 edly connected link members, whereof each member comprises toothed end portions, spaced parallel bars connecting said portions, a plurality of spaced cross-pieces connecting the bars, posts on said cross-pieces 35 extending between the bars, and U-shaped springs fastened to the outer ends of the posts so that the limbs of the springs extend adjacent to the inner sides of the respective bars.

Signed at Barberton in the county of 40 Summit and State of Ohio this 5th day of July A. D. 1916.

MICHAEL PARIDON.
